FLUSH TANK ATTACHMENT

Eddie J. Goodman and Jennings W. Bibee,
Lynchburg, Va.

Application March 8, 1937, Serial No. 129,752

7 Claims. (Cl. 4—41)

This invention relates to a flush tank attachment and more particularly to a device adapted to be mounted in a flush tank and engage the swinging arm of a float valve to secure the arm and the float carried thereby against downward movement until an arm-engaging member of the attachment is moved to a releasing position.

Flush tanks as now made include as part of their equipment a rubber ball valve for the outlet which moves upwardly when in an opened position and seats itself when the tank is emptied. The rubber valve is seated with considerable force and this causes the valve to be worn so that a complete closure is not effected and water will trickle through the flush pipe into the bowl. A great deal of water is wasted in this manner and in addition many persons find the noise of the trickling water very annoying.

It is, therefore, one object of the invention to provide an attachment which, when mounted in a flush tank, will serve to engage the arm or lever of the inlet valve and secure the float controlled inlet valve in a closed position. It will thus be seen that, when the ball valve for the outlet becomes worn, water may drain out of the tank, but the float valve for the inlet will be held closed and waste of water prevented and also the annoying sound of water trickling into the bowl eliminated.

Another object of the invention is to so construct the attachment that it may be very easily mounted in a flush tank of a conventional construction with its latch or keeper disposed in position for engagement by the arm or lever of the float valve as the arm and the float thereof move upwardly during filling of the tank.

It is another object of the invention to provide the attachment with means for guiding the arm or lever of the float valve into position for engagement by the latch or keeper during its upward movement and thus insure proper engagement of the arm or lever with the keeper when the tank is filled.

It is another object of the invention to provide the latch or keeper with a weight which may be adjusted in order to impart proper balance to the latch or keeper and thus permit the keeper to be easily moved into position to engage under the arm or lever of the float valve as this arm moves upwardly.

Another object of the invention is to provide the attachment with means for engagement by an actuating member carried by an arm or lever of the mechanism for drawing the valve ball upwardly out of closing relation to the outlet of

the tank and thus cause the arm of the float valve to be released so that this arm or lever and its float may move downwardly as the tank is emptied and cause the inlet valve to be opened for refilling of the tank.

The invention is illustrated in the accompanying drawing, wherein

Figure 1 is a perspective view showing the attachment applied to a flush tank of a conventional construction.

Figure 2 is an enlarged view of the attachment and showing the same partially in side elevation and partially in section, and

Figure 3 is a fragmentary sectional view taken through the attachment along the line 3—3 of Figure 2.

In Figure 1, there has been shown a flush tank 1 of a conventional construction and provided with the usual outlet pipe or flush pipe 2 leading to a bowl 3. The usual feed pipe or inlet pipe 4 has also been provided and, at its inner end which is not shown, the pipe has applied thereto the usual float valve which includes the arm or lever 5 carrying a float 6 at its free end. There has also been provided the usual ball valve 7 for the flush pipe 2, the stem 8 of which extends through a guide 9 and is loosely engaged by the link or grapple 10 mounted in the usual manner upon the free end of the arm or lever 11 of the release mechanism which is of a conventional construction and actuated by means of the usual handle 12. The mechanism so far described is of a conventional construction and, when the handle 12 is swung upwardly in either direction from a depending position shown in Figure 1, the valve ball 7 will be drawn upwardly out of closing relation to the flush pipe. When the valve ball 7 is drawn upwardly, its buoyancy causes it to rise and as the level of the water in the tank approaches the bottom thereof the valve ball moves downwardly with the water until it is finally reseated in closing relation to the outlet from which the flush pipe extends. A severe blow is imparted to the valve ball as it is seated in closing relation to the outlet and after the valve ball has been in use for sometime it becomes worn to such an extent that a complete closure is not effected. Water will then leak from the tank through the flush pipe which will lower the level of the water in the tank to such an extent that the float valve of the inlet pipe 4 will not be completely closed. This causes waste of water and in addition water leaking from the tank through the pipe 2 into the bowl 3.

creates a noise which is very disagreeable to many people.

The attachment constituting the subject-matter of this invention serves to retain the float valve closed after the tank has been filled and in case the valve ball 7 has become worn only the water which is in the tank after it has been filled will be wasted. The fact that no water flows from the tank through the flush pipe 2 when the handle 12 is operated will clearly indicate that the valve ball needs replacement.

This attachment is adapted to be applied to the tank as an accessory and, when in place, it extends transversely of the tank between the front and rear walls 13 and 14 thereof, as shown in Figures 1 and 2. The main bar or bridge 15 is formed from strong metal which may be brass or any other desired material and has its end portions threaded, as shown at 16 and 17. A collar 18 is screwed upon the threaded end portion 16 of the rod or bar 15 and a cap 19 is screwed upon the threaded end portion 17 of the bar. The collar 18 carries a set screw 20, by means of which it may be secured in a set position upon the threaded end of the bar and the annular flange 21 of this collar carries screws 22 which are preferably three in number and have abutting engagement with the inner surface of the rear wall 14 of the tank and frictionally grip the same to prevent turning of the bar 15 when the cap 19 is turned to move the apex of its tapered end 23 into engagement with the inner surface of the front wall 13 of the tank. The tapered end portion of the cap 19 is solid, as clearly shown in Figure 2, and aligned openings 24 are formed through the cylindrical portion of the cap to receive a turning tool. It will thus be seen that the cap may be turned until its apex bites into the front wall of the tank and, if found necessary, a screw driver may be applied to the set screws 22 to tighten them. The bar 15 will thus be very firmly mounted transversely in the tank over the lever 5 of the float valve and will be prevented from slipping out of place or turning in the collar and the cap.

A sleeve 25 fits about the bridging bar 15, and upon referring to Figure 2, it will be seen that this sleeve is formed from a thick and cylindrical block of brass or other metal formed with a bore 26 to snugly receive the bar 15. Set screws 27 and 28 are threaded through the sleeve 25 midway the length thereof in opposed relation to each other, the set screw 28 being formed with a lug or tooth 29 at its inner end to engage in the groove 30 formed longitudinally of the bar for the entire length thereof. By so forming and mounting the sleeve it may be adjusted longitudinally upon the bar and dispose the depending rod 31 at opposite sides of the lever 5 in equal spaced relation thereto. The lug 29 of the set screw 28 will prevent the sleeve from turning about the bridging bar 15, and when the set screw 27 is tightened the sleeve will be firmly secured in a set position upon the bridging bar and prevented from slipping longitudinally thereof out of a desired position.

The lever 5 of the float valve is to be releasably secured in a raised position when the tank is filled and the float valve closed, and in order to do so, there has been provided a latch or keeper 32 formed from a length of metal rod which is also preferably brass. This rod is bent intermediate its length to provide the latch or keeper with a shank 33 and an arm 34 extending horizontally from the upper end of the shank. The

lower end of the shank forming portion of the rod is bent back to form a bill 35 extending diagonally upwards in diverging relation to the shank and terminating in an inwardly extending and substantially horizontal arm 36 to engage under and support the lever 5. By having the bill 35 extend upwardly at an incline in diverging relation to the shank of the latch a cam action may take place between the lever 5 and the bill 35 as the lever and its float 6 move upwardly and thus cause the latch to be swung about its pivot 37 to a position in which the lever 5 may move upwardly beyond the bill and the bill then returned to its initial position in which the arm 36 engages under the lever 5 and supports the same. An abutment screw 38 is carried by the sleeve 25 and projects laterally therefrom to limit movement of the bill under the arm or lever 5 beyond the position shown in Figure 2. The pivot pin 37 consists of a screw which is threaded into the sleeve and formed with the usual head at its outer end which retains the latch or keeper in place upon the screw. The free end portion of the arm 34 is threaded, as shown at 39, and this threaded portion extends from the major portion of the length of this arm in order that the weight 40 may be adjusted along the arm to a position in which the bill will be caused to move quickly under the lever 5 into supporting engagement with the lever. At the same time the weight should be so adjusted that upward movement of the lever and engagement of the lever with the diagonally extending bill may easily swing the keeper out of the way and permit the lever and its float to move upwardly into position to close the float valve of the feed pipe. A lug or ear 41 extends upwardly from the weight 40 and is formed with a slot or opening 42 to loosely receive an actuating rod 43. This rod 43 is secured to the actuating arm 11, by means of which the valve ball 7 is unseated, and from an inspection of Figures 1 and 2, it will be readily appreciated that, when the arm 11 is swung upwardly to draw the valve ball upwardly out of closing relation to the flush pipe 2, the latch or keeper will be swung about its pivot 37 and move its bill out of a position under the lever 5. The lever 5 and its float can then move downwardly as water flows out of the tank through the flush pipe. When the handle 12 is released, the weight 40 will cause the latch or keeper to be returned to the normal position shown in Figure 2, and as the lever 5 is moved upwardly during filling of the tank, the latch will be swung out of the way and then returned to its normal position for engagement under the lever. When the valve ball 7 is in good condition, water will remain in the tank, but if the valve ball is worn, water will leak from the tank through the flush pipe until the tank is empty. In view of the fact that the float valve for the feed pipe will be kept closed, no more water can escape. The fact that water has emptied from the tank will indicate that a new valve ball is necessary.

Having thus described the invention, what is claimed as new is:

1. An accessory for a flushing device which includes a flush tank, a float valve, a ball valve for the outlet of the tank and an actuating arm for the valve ball; said accessory comprising latch-
ing means for releasably holding the float valve closed, and means for moving the latching means out of engagement with the float valve adapted to be connected with and actuated by the actuating arm of the ball valve.

2. An accessory for a flushing device which includes a flush tank, a ball valve for the outlet of the tank, actuating means for unseating the ball valve, and a float valve having an actuating arm and a float carried thereby; said accessory comprising a support adapted to be mounted in said tank, a latch carried by said support and movable into and out of position to engage the arm of the float valve and releasably retain the float valve closed, and means for moving said latch out of engagement with the arm of the float valve adapted to be operatively connected with the actuating means for the ball valve.

3. An accessory for a flushing device which includes a flush tank, a ball valve for its outlet, actuating means for unseating the ball valve, and a float valve for the inlet pipe of the tank including an actuating arm and a float carried thereby; said accessory constituting means for controlling opening of the float valve when the tank is emptied and comprising a support adapted to be mounted in said tank over said arm, a latch carried by said support and movable into and out of position to engage under the arm of the float valve and releasably hold the arm in an elevated position with the float valve closed, and means adapted to be carried by the actuating means for the ball valve and move the latch out of engagement with the arm of the float valve when said actuating means is operated to unseat the ball valve.

4. In combination with a flush tank including a ball valve for the outlet of the tank, actuating means for unseating the ball valve, and a float valve for the inlet pipe of the tank including an arm and a float carried thereby; means for releasably securing the float valve closed during emptying of the tank by leakage through the outlet thereof, said means comprising a support mounted in said tank, a latch pivoted to said support and having a bill for engaging under the arm of the float valve when the tank is full, a cam portion being provided for engagement by the arm of the float valve whereby the latch may be swung about its pivot during upward movement of the arm of the float valve and then swing into position to engage under the arm, and means carried by the actuating means for the ball valve engaging said latch and moving the latch out of engagement with the arm of the float valve when the said actuating means is operated to unseat the ball valve.

5. A float tank attachment comprising a support adapted to be mounted in a float tank and

extend over the actuating arm of a float valve transversely thereof, a latch carried by said support and movable into and out of position to engage under the arm of the float valve and hold the float valve closed, and actuating means for said latch adapted to be connected with actuating mechanism for an outlet valve of a tank and moved thereby to move the latch out of engagement with the arm of the float valve during unseating of the outlet valve.

6. A flush tank attachment comprising a supporting bar, means to mount said bar in a tank over the operating arm of a float valve transversely thereof, a sleeve adjustable along said bar, a latch pivoted to said sleeve for movement into and out of position to engage under the arm of the float valve and maintain the float valve closed, and means for moving said latch out of engagement with the arm of the float valve adapted to be actuated when an outlet valve for the tank is opened.

7. A flush tank attachment comprising a mounting bar, members adjustably carried by ends of said bar for engaging walls of a tank and supporting the bar in the tank transversely thereof over the actuating arm of a float valve, a sleeve slideable along said bar, means to secure said sleeve in a set position upon the bar and prevent turning of the sleeve about the bar, rods depending from said sleeve and spaced from each other longitudinally thereof for disposition at opposite sides of the arm of the float valve to guide vertical movement of the arm during emptying and filling of the tank, a latch pivoted to said sleeve and having a bill for engaging under the arm of the float valve when the tank is filled and the float valve closed, said bill having a diagonally extending portion constituting a cam surface engageable by the arm of the float valve during upward movement of the arm whereby the bill will be swung transversely of the arm during upward movement thereof and then swing into place under the arm in supporting engagement therewith, an arm for said latch extending horizontally, a counter-weight upon the arm of the latch adjustable longitudinally thereof, and means for connecting said weight with actuating means for an outlet valve of a tank whereby said latch will be moved out of engagement with the arm of the float valve during opening of the outlet valve.
